UNITED STATES PATENT OFFICE

ALFRED A. BRIGGS AND JOSIAH A. BRIGGS, OF NEW YORK, N. Y.

FLUSH-TANK FIXTURE

Application filed November 10, 1928. Serial No. 318,406.

This invention relates to flush tank fixtures and particularly to valve mechanism and controlling mechanism for initiating the flow of or discharge of water from the tank.

- 5 One of the objects of the invention is to provide a tank fixture of the character described that is simple in construction, comprises few parts, and may be economically manufactured.
- 10 Another object of the invention is to provide a fixture that is positive and quiet in operation and in which the parts are so constructed and arranged that they will not be thrown out of adjustment in use.

- 15 Another object of the invention is to provide a construction that is rugged and will operate effectively and quietly without the use of packings, washers or similar devices.

- 20 Another object of the invention is to provide a flush tank fixture so constructed and arranged that successive discharges from the tank will be obtained.

- 25 Further objects of the invention will appear from the following specification taken in connection with the drawings, which form a part of this application, and in which

- 30 Fig. 1 is a sectional elevation of a tank having a fixture therein constructed in accordance with the invention;

- 35 Fig. 2 is a sectional elevation of the structure shown in Fig. 1 taken substantially on line 2—2 of Fig. 1;

- 40 Fig. 3 is a top plan of the valve mechanism shown in Fig. 1;

- 45 Fig. 4 is a sectional elevation of one of the valve mechanisms taken substantially on line 4—4 of Fig. 2;

- 50 Fig. 5 is a sectional elevation of the other valve mechanism taken substantially on line 5—5 of Fig. 2;

- Fig. 6 is a sectional elevation similar to Fig. 1, partly broken away, and showing another form of fixture constructed in accordance with the invention; and

- 55 Fig. 7 is a top plan view of the structure shown in Fig. 6.

- The invention briefly described consists of a flush tank fixture comprising a U-shaped flush or outlet pipe, one leg of the U-shaped pipe extending downwardly into the tank

and receiving water therefrom and the other leg extending downwardly through the bottom of the tank. A valve casing communicates with the inlet leg of the pipe and when the valve in the casing is opened, water from the pressure main is injected into the inlet leg and initiates the flow of water through the flush pipe. The water under pressure forces the air and water around the bend of the U-shaped flush pipe and sets in operation the siphon action, whereby the tank will be emptied. In the form of the invention illustrated, the flow of water through the valve chamber into the flush pipe and also the flow into the tank to replenish the tank are valve controlled.

Further details of the invention will appear from the following description.

The invention illustrated and to be described in this application constitutes a simplification of and an improvement on the invention covered by Patent No. 1,519,188 to Alfred A. Briggs, granted December 16, 1924.

55 In the embodiment of the invention illustrated in Figs. 1 to 4 inclusive of the drawings, there is shown a flush tank 10 having secured thereto a U-shaped siphon or flush pipe having its inlet leg 11 extending downwardly to a position adjacent the bottom of the tank 80 and having its outlet leg 12 extending through the bottom of the tank about four inches to form an air chamber between the bowl and the bottom of the tank. The lower end of the outlet leg 12 discharges into a pipe 9 secured to the bottom of the tank and surrounding and spaced from the end of pipe 12. As shown in Fig. 1, the inlet leg 11 is slightly larger in cross section than the outlet leg 12.

85 The inlet leg 11 of the flush pipe is interrupted, as shown at 13, and an annular casing 14 is secured to this portion of the leg 11. The casing 14 has an annular chamber 15 surrounding the leg 11 and has a conical wall 16 disposed above the conical upper end 17 of the lower portion of the leg 11. The casing 18 is connected as shown at 18 to the upper portion 11A of the inlet leg 11 and the lower portion of the inlet leg is adjustably threaded, as shown at 19, to the casing. A lock nut 20

100

secures the lower portion of the leg 11 in adjusted position.

From the foregoing description it will be seen that a conical opening is formed between the upper end 17 of the lower portion of the inlet leg and the portion 16 of the inner wall of the casing.

The casing chamber 15 has communicating therewith, a conduit 25. A pipe 26 is connected at one end to the conduit 25 and at its opposite end to a T-shaped coupling 27 which communicates at one end with a valve casing 28 having upper and lower chambers 29 and 30. The upper chamber 29 of the valve casing 28 receives water from a pressure main 31 which, as shown at 32, extends downwardly through the bottom of the tank. The coupling 27 communicates at one end with the chamber 30 of the valve casing and at the opposite end the coupling communicates with a valve controlled water inlet pipe for refilling the tank, hereinafter described.

A valve port 38 establishes communication between the chambers 29 and 30 and the flow of liquid through this port is controlled by a valve 40 which is adapted to seat on the port 38.

Valve 40 has connected thereto a valve stem 41 having an enlarged portion 42 slidably mounted in a tubular extension 43 which projects downwardly from the valve casing 28. The enlarged portion 42 of the valve stem has a slot 45 therethrough and the tubular extension 43 is slotted to permit the passage therethrough and through the slot 45 of a valve control lever 50. The lever 50 is pivoted at 51 on lugs carried by the tubular extension 43 and has a spherical portion 52 disposed in the slot 45 of the enlarged portion of the valve stem.

The lower end of the tubular extension 43 is closed by a plug 55 and the portion of the valve stem below the slot 45 has formed therein a conduit having a downwardly extending portion 56 and a laterally extending portion 57. 56 extends above 57 to form an air pocket in which air is compressed, which takes care of the last one-sixteenth inch of valve travel. The portion 57 of the conduit is so located that when the valve is opened by the lever and the valve stem is disposed in its uppermost position, the outer end of the portion 57 of the conduit will communicate with the slot or opening in the extension 43 through which the lever 50 passes, as shown in dotted lines, (Fig. 4).

A conduit 60 communicates at one end with the chamber 30 in the valve casing and at its opposite end communicates with the lower end of the tubular extension 43 after the lower end of the enlarged portion of the valve stem has started its upward movement.

One end of the lever 50 has connected thereto an arm 65 to which is secured a ball float 66.

The other end of the lever has formed therein a vertical slot 67 through which extends a link 68 having adjustably mounted on its lower end below the lever, a nut 69. The opposite end of the link 68 is connected to a crank 70 mounted on a spindle 71 journaled in a wall of the tank and extending therethrough. The outer end of the spindle 71 has secured thereto an arm 75, by means of which the crank and spindle can be rotated in either direction to lift the lever 50, depress ball 66, and open the valve 40. A second slot 76 may be provided in the lever 50 for the purpose of securing adjustment in the connection of the link 68 to the lever.

The admission of water from the pressure main into the tank to refill the tank after it has been emptied is controlled in the following manner. The T-shaped coupling 27, as above stated, is connected at one end to the valve chamber 30, from which the water is conducted to the inlet leg of the siphon pipe and is connected at its other end to a valve chamber 80 formed in a valve casing 81. The chamber 80 communicates with a chamber 82 through a port 83 controlled by a valve 84 having a valve stem 86 slidably mounted in a boss 87 formed on the valve casing 81. The valve 84 is controlled by a lever 90 pivoted at one end, as shown at 91, (Figs. 3 and 5) to a bracket 92 carried by the valve casing 81. The lever is pivoted at 93 to the valve and has secured to the end opposite the pivoted end, a ball float 94 relatively small in size. An adjustable stop 96 is mounted on a lug 97 carried by the casing 81 for limiting the downward movement of the lever. The float 94 is carried by a post 98 adjustably secured to the end of the lever 90.

From the foregoing description it will be evident that as the water in the tank is emptied through the U-shaped discharge pipe and the level of the water is lowered, the float 94 will fall and open the valve 84, thus permitting the water from the pressure main to pass through the port 83 from the chamber 80 and into the chamber 82. From this chamber the water passes downwardly through the tank refill pipe 99 to replenish the supply of water in the tank.

The construction of the valve control mechanism for directing a stream of water under pressure into the siphon or flush pipe is the same in the form of the invention illustrated in Figs. 6 and 7 as that illustrated in Figs. 1 to 5 inclusive and above described. Therefore, the same reference characters have been used in Figs. 6 and 7 and further description of this mechanism is unnecessary.

In the form of the invention shown in Figs. 6 and 7, the float controlled valve mechanism for controlling the refilling of the tank is not used. The T-shaped coupling has connected thereto a valve casing 100 having therein a valve controlled by a handle 101. A pipe 102

is connected to the opposite end of the valve casing and extends downwardly to a position adjacent the bottom of the tank. The valve in the casing 100 can be adjusted to the desired position to regulate the flow of water from the T-shaped coupling into the refill pipe 102.

Operation

The fixture shown in Figs. 1 to 5 inclusive and above described, operates in the following manner: The normal water level in the tank is indicated by the dot and dash lines in Figs. 1 and 2. When the tank is to be emptied, the crank 70 will be rotated, thus lifting the lower end of the lever 50 and causing the lever to lift the valve stem 41 and open the valve 40. The water from the pressure main will then be permitted to flow from the chamber 29 into the chamber 30 of the valve casing. The water then flows through the coupling 27 and pipe 26, into the chamber 15 surrounding the inlet leg of the U-shaped flush pipe. The pressure of the water will direct a conical stream into the inlet leg through the conical opening between the surfaces 16 and 17, and this stream will positively lift the water in the upper end 11A of the U-shaped connecting coupling between the legs 11 and 12. This column of water will force before it any air in the U-shaped flush pipe and will completely fill the outlet leg, due to the difference in diameter between the inlet and outlet legs of the flush pipe.

At the time water is admitted to chamber 30 it is also in communication with chamber 80. Upon the first depression of valve 84 some of the water from the main 31 will enter the tank through the pipe 99. The adjustment provided for by the screw 96 makes it possible to regulate the amount of opening of the valve 84 in accordance with the available pressure. If a high pressure is available, the valve 84 may be moved downwardly to a considerable extent, which will permit a comparatively large amount of water from main 31 to enter the tank directly through pipe 99. If the available water pressure is low, the adjustment is so made as to give but a slight opening movement to valve 84, so that but little water enters the tank to level it through pipe 99. In either case, however, the full available pressure is present for the initiation of the siphon action through the conduit 25.

After the flow has been started in the manner just described, it will continue by siphon action, assisted by pressure in the main, through 16 and 17, which flows continuously until float 66 raises and closes valve 40, thus giving a greater force to the siphon and more thoroughly cleaning the bowl. It has been found in actual practise that the discharge takes place in successive increments or in successive discharges from the tank and this action is advantageous since it increases the effectiveness of the flushing action.

The action just mentioned takes place in the following manner: As shown in Fig. 1, the discharge pipe 9 empties into a pipe 103 which leads to the bowl to be flushed. Pipe 103 is smaller in diameter than the pipe 9 and, therefore, as the flow from the tank passes into the pipe 9, it will back up, compressing the air in the space surrounding the lower end of the discharge leg of the siphon pipe and the upper end of the pipe 9. After the water is substantially discharged from the pipe, the pressure in the air chamber described will force the remaining water out of the pipe 9, thus causing an added increment of water to be discharged into the bowl. This will also be assisted by the water which is being received from the pressure main, as the valve 40 will remain open until the float control 66 closes the valve as the float reaches its uppermost position. When the water level has been reduced in the tank to a sufficient extent, the float 94 which controls the valve 84 will cause this valve to open, thus admitting water to the refilling pipe 99 and effecting the refilling of the tank.

During the operation of the valve 40, a cushioning action will be obtained in the lower end of the tubular extension 43 in the following manner. During the raising of the valve stem by the lever 50, water will enter the lower end of the tubular extension 43 through the conduit 60. As the valve is closing, a portion of this water will be permitted to escape through the conduit 56, 57. However, when the valve stem has been lowered to a sufficient extent for the outlet end of the portion 57 of the conduit to be closed, the remaining water will be trapped in the lower end of the extension 43, thus cushioning the closing action of the valve.

The valve mechanism controlling the admission of water from the pressure main to the flush pipe in the form of the invention illustrated in Figs. 6 and 7, operates in the same manner as the corresponding valve mechanism in the other embodiment of the invention. In the structure shown in Figs. 6 and 7, however, the level of the tank is not controlled by separate valve mechanism and the tank is levelled by the water which passes from the pressure main through the coupling, through the valve casing 100, and refilling pipe 102. After the water has again reached normal level in the tank, the float 66 will cause the valve 40 between the chambers 29 and 30 to be closed, thus shutting off the flow of water to the refilling pipe.

From the foregoing description it will be clear that a simple, practical and efficient flush tank fixture has been designed. Furthermore, the operation of the device will be noiseless.

Although certain specific embodiments of the invention have been particularly shown

and described, it will be understood that the invention is capable of further modification and that further changes in the construction and in the arrangement of the various cooperating parts may be made without departing from the spirit or scope of the invention, as expressed in the following claims.

What we claim is:

1. In a flush tank fixture, a tank, a U-shaped outlet pipe having one leg extending to a position adjacent the bottom of the tank and the other leg extending through the bottom of the tank, means for upwardly directing a stream of water under pressure into the inlet leg of the pipe, and a discharge pipe surrounding the outlet leg of the pipe and spaced therefrom to provide an air chamber and having a restricted orifice spaced from said air chamber.
2. In a flush tank fixture, a tank, a U-shaped outlet pipe having an inlet leg extending to a position adjacent the bottom of the tank and an outlet leg extending through the bottom of the tank, a valve casing having a chamber therein, a pressure main adapted to supply water under pressure to said chamber, a port between said pressure main and said chamber, a valve controlling said port, conduit means connecting said chamber to the inlet leg of the U-shaped pipe, a valve stem housing, a valve stem connected to the valve and disposed in said housing, and a by-pass conduit connecting said chamber and said housing, the connection between the by-pass and housing being disposed above the lower extreme position of the stem and below the upper extreme position of the stem.
3. In a flush tank fixture, a tank, a U-shaped outlet pipe having an inlet leg extending to a position adjacent the bottom of the tank and an outlet leg extending through the bottom of the tank, a valve casing having a chamber therein, a pressure main adapted to supply water under pressure to said chamber, a port between said pressure main and said chamber, a valve controlling said port, conduit means connecting said chamber to the inlet leg of the U-shaped pipe, a valve stem housing, a valve stem connected to the valve and disposed in said housing, and a conduit in the lower portion of the valve stem having one end open in the upper extreme position of the valve stem and closed as the stem and valve move downwardly to close the valve.
4. In a flush tank fixture, a tank, a U-shaped outlet pipe having an inlet leg extending to a position adjacent the bottom of the tank and an outlet leg extending through the bottom of the tank, a valve casing having a chamber therein, a pressure main adapted to supply water under pressure to said chamber, a port between said pressure main and said chamber, a valve controlling said port, conduit means connecting said chamber to the inlet leg of the U-shaped pipe, a valve stem housing, a valve stem connected to the valve and disposed in said housing, a conduit in the lower portion of the valve stem having one end open in the upper extreme position of the valve stem and closed as the stem and valve move downwardly to close the valve, and a by-pass conduit connecting said chamber and said housing, the connection between the by-pass and housing being disposed above the lower extreme position of the stem and below the upper extreme position of the stem.
5. In a flush tank fixture, a tank, a flush pipe extending through the bottom of the tank, a pressure pipe extending into the tank and adapted to communicate with the flush pipe and with the tank, a valve for controlling the pressure pipe, a lever connected to control said valve, a float on one end of said lever, means connected to one end of the lever for tilting the lever to open the valve, another valve for controlling the flow of water into the tank, said other valve having a lever and a float, and adjustable means for limiting the movement of said lever.
6. In a flush tank fixture, a tank, a U-shaped outlet pipe having an inlet leg extending to a position adjacent the bottom of the tank and an outlet leg extending through the bottom of the tank, a valve casing having a pair of chambers therein, a pressure main connected to one of said chambers, a port opening between the chambers, a valve controlling said port, means connecting the other chamber to the inlet leg of the U-shaped pipe, said means including a structure for directing an inwardly converging conical stream upwardly into said inlet leg, and a conduit leading from the last named chamber to said tank.
7. In a flush tank fixture, a tank, a U-shaped outlet pipe having an inlet leg extending to a position adjacent the bottom of the tank and an outlet leg extending through the bottom of the tank, a valve casing having a pair of chambers therein, a pressure main connected to one of said chambers, a port opening between the chambers, a valve controlling said port, means connecting the other chamber to the inlet leg of the U-shaped pipe, said means including a structure for directing an inwardly converging conical stream upwardly into said inlet leg, a conduit leading from the last named chamber to said tank, a float controlled valve in said conduit, and means for adjusting the degree of opening of said float controlled valve.
